Attorney

UNITED STATES PATENT OFFICE.

HARRY F. SHINDEL, OF READING, PENNSYLVANIA, ASSIGNOR TO WILLSON PRODUCTS, INC., OF READING, PENNSYLVANIA, A CORPORATION OF PENNSYLVANIA.

VALVE DEVICE FOR RESPIRATORS OR THE LIKE.

Application filed February 18, 1927. Serial No. 169,215.

My invention relates to respirators or like devices which comprise a close-fitting air-chamber having suitable provision for inhaling and a separate exhaling outlet, and it consists in an improved valve arrangement for the latter as fully described in connection with the accompanying drawing and clearly defined in the subjoined claim.

Fig. 1 is a diagrammatic side elevation of a respirator having my improved outlet valve applied thereto; Fig. 2 is an enlarged fragmentary cross-section of the chamber wall with the valve applied thereto, taken on the line 2—2 of Fig. 1; Figs. 3 and 4 are respectively an edge view and an inner plan view of the valve cap; and Fig. 5 is a separate view of the flap valve which is operatively retained by the cap.

The respirator indicated comprises a cup shaped air chamber *a*, formed of soft rubber and adapted to fit closely to the face of the wearer, its open contracted forward portion being provided with a suitable casing *b* adapted to contain suitable filling material through which the inhaled air passes; a separate outlet opening *c* being provided in the chamber wall for discharge of the exhaled air.

In my improved construction the wall outlet opening *c* is provided with an exterior circular boss *5*; which boss forms a seat for the rim portion *6* of a disc valve having an integral flap *7* adapted to normally close the opening, and is also provided with a peripheral circular groove *8* adapted to be engaged by the valve cap separately shown in Figs. 3 and 4.

This valve cap 10 is formed of sheet material pressed to cup shape as shown; the rim flange thereof having portions 11 which are adapted to fit over the wall boss 5, with in-

tervening notched portions 12. These notched portions 12 of the cap flange are set outward from the boss-engaging portions 11 so as to provide free discharge openings 13, 45 through the cup flange when the valve flap 7 is opened by exhaling pressure; the increased diameter of the notched flange portions 12, extending below the valve-seating face of the boss 5 but being spaced away 50 from the periphery of the latter; and the boss-fitting flange portions 11 being formed with interior offsets 14 which press the rim portion 6 of the valve to its seat upon the boss when the cap is in place upon the latter; 55 and also having interior radial projections 15 which serve as detents adapted to engage in the peripheral groove 8 of the boss when the cap is so placed. My improved valve cap thus provides a very simple and neat 60 valve-securing device which is adapted to permit free discharge of the exhaled air while forming a very satisfactory covering of the wall opening, and which is very securely retained in place though readily removable when desired. The specific form set forth may be readily modified within the 65 invention as defined in the claim.

What I claim is:

In combination with a chamber-enclosing 70 respirator-wall or the like having a discharge aperture with a surrounding valve-retaining boss; a valve device comprising a flap-valve seating upon said boss, and a valve-retaining cap having an annular flange 75 with spaced apart boss-engaging portions having valve-contacting offsets and intervening portions of enlarged diameter having air-escape notches.

In testimony whereof I affix my signature.

HARRY F. SHINDEL.
